UNITED STATES PATENT OFFICE

169,938

RAILWAY CAR BODY

Alfred B. Girardy, Park Forest, Clarence V. Norby, Chicago, and Donald W. Doman, Harvey, Ill., assignors to Pullman-Standard Car Manufacturing Company, Chicago, Ill., a corporation of Delaware

Application October 13, 1952, Serial No. 21,822

Term of patent 14 years

(Cl. D66—1)

To all whom it may concern:

Be it known that we, Alfred B. Girardy, Clarence V. Norby, and Donald W. Doman, citizens of the United States of America and residents, respectively, of Park Forest, county of Cook, and State of Illinois; Chicago, county of Cook, and State of Illinois; and Harvey, county of Cook, and State of Illinois, have invented a new, original, and ornamental Design for a Railway Car Body, of which the following is a specification, reference being had to the accompanying drawings, forming part thereof.

In the drawings:

Fig. 1 is a perspective view of a railway car body showing our new design having portions broken away better to reveal the disposition of the cocktail lounge within the vehicle, the supporting trucks being shown in dotted lines for illustrative purposes only;

Fig. 2 is a horizontal mid-sectional view taken through the vehicle showing the lounge;

Fig. 3 is a vertical longitudinal sectional view through the vehicle showing the lounge, taken on the line 3—3 of Fig. 2;

Fig. 4 also is a vertical longitudinal sectional view through the vehicle showing the lounge, taken on the line 4—4 of Fig. 2;

Fig. 5 also is a vertical longitudinal sectional view through the vehicle looking at the lounge, taken on the line 5—5 of Fig. 2;

Fig. 6 is a vertical transverse sectional view through the vehicle showing the lounge, taken on the line 6—6 of Fig. 2;

Fig. 7 also is a vertical transverse sectional view through the vehicle showing the lounge, taken on the line 7—7 of Fig. 2;

Fig. 8 also is a vertical transverse sectional view through the lounge, taken on the line 8—8 of Fig. 2; and

Fig. 9 is a general perspective view of the lounge in the railway car body.

The characteristic features of the present design reside in the interior lounge design shown in the drawings.

We claim:

The ornamental design for a railway car body, substantially as shown and described.

ALFRED B. GIRARDY.
CLARENCE V. NORBY.
DONALD W. DOMAN.
